Primary Examiner — Paula Allen Greene

(57) **CLAIM**

The ornamental design for an ear bud pair, as shown and described.

DESCRIPTION

FIG. 1 is a front view of an ear bud pair showing my new design;

FIG. 2 is a rear view of the ear bud pair;

FIG. 3 is a right side view of the ear bud pair;

FIG. 4 is a left side view of the ear bud pair;

FIG. 5 is a top view of the ear bud pair;

FIG. 6 is a bottom view of the ear bud pair; and,

FIG. 7 is a top front side perspective view of the ear bud pair.
